Christian Anderson, Inventor.

UNITED STATES PATENT OFFICE.

CHRISTIAN ANDERSON, OF CHIPPEWA FALLS, WISCONSIN.

CUTTER-HEAD.

SPECIFICATION forming part of Letters Patent No. 632,618, dated September 5, 1899.

Application filed December 6, 1898. Serial No. 698,464. (No model.)

To all whom it may concern:

Be it known that I, CHRISTIAN ANDERSON, a citizen of the United States, residing at Chippewa Falls, in the county of Chippewa and 5 State of Wisconsin, have invented a new and useful Cutter-Head for Planing-Machines, of which the following is a specification.

My invention relates to cutter-heads for surface-planers and jointer-heads; and the object in view is to provide a simple and improved construction of cylinder and knife-secur- 10 ing devices whereby a knife consisting of a flat straight-edged plate may be employed and may be promptly and effectually secured 15 in place to cause an efficient coöperation of the several knives carried by the cylinder.

Further objects and advantages of this invention will appear in the following description, and the novel features thereof will be 20 particularly pointed out in the appended claims.

In the drawings, Figure 1 is a perspective view of a cutter-head constructed in accordance with my invention. Fig. 2 is a trans- 25 verse section of the same, taken partly in the plane of one of the circumferential channels. Fig. 3 is a detail view of a portion of one of the blade-secur- 30 ing wedges.

Similar reference characters indicate corre- 30 sponding parts in all the figures of the drawings.

1 designates a cylinder which is provided in its periphery with a series of longitudinal grooves 2, forming knife-seats. These grooves 35 are cross-sectionally tapered from the surface of the cylinder inward, and the knives 3, which are arranged in the grooves in contact with one of the side walls thereof, preferably do not extend to the bottom of the grooves, 40 but terminate adjacent to offset shoulders 4, formed upon the walls against which the knives rest. The knives are secured in the seats by means of cross-sectionally wedge-shaped strips 5, which may extend continu- 45 ously from one end of the cylinder to the other, or, in other words, may consist of a single bar or may be sectional, as preferred. The wedges or knife-holding strips are preferably concave at their outer edges adja- 50 cent to the blade and convex adjacent to the wall of the seats remote from the blade

and are so proportioned with relation to the grooves in which they fit as to terminate at their inner edges short of the floors or bottoms of the grooves to adapt them for ad- 55 justment as the contacting faces of the parts become worn. These strips are held in place by means of adjusting devices consisting of bolts or screws 6 or the equivalent thereof, which extend through the strips from 60 their outer to their inner edges, with the heads or nuts at their outer ends suitably countersunk to avoid projection. By having the strips formed at their outer edges in the manner shown—that is, with their forward 65 edge portion convex and their rear edge portion concave—the divergent sides or faces of the strips obtain a bearing against the divergent walls of the knife-seats throughout their extent and the concaved edge portion affords 70 clearance for the cuttings or chips. The inner ends of these securing and adjusting bolts are engaged with the floors of the 75 grooves, or, preferably, as shown in the drawings, with gibbs 7, which are cross-sectionally doyetailed to fit in corresponding cross-sectionally-shaped ways 8 in the floors or bottoms of the grooves. In the construction illustrated the adjusting devices 6 consist of cap-screws, which extend inwardly from the 80 outer edges of the wedges with their heads arranged in the countersinks and with their inner ends threaded in suitable sockets formed in the gibbs, and by reason of the adjustable fitting of the gibbs in the ways pro- 85 vided therefor adjustment of the wedge is allowed longitudinally of the cylinder. These adjustable gibbs, however, are of particular advantage in connection with the sectional wedges 5^a, (illustrated in Fig. 1,) in that they 90 provide for securing in place bits when the machine is to be used as a matcher or beader. The members of the wedge or knife-holding strip may be adjusted to suit the desired positions of the bits. 95

In connection with the adjustment of the knives or bits suitable gages (not shown in the drawings) may be employed; but in order that the knives may be moved outward when desired to secure a uniform adjustment there- 100 of I preferably provide the cylinder with circumferential channels 9 of sufficient depth

to extend approximately to the floors of the knife-seats, whereby a thin-bladed instrument may be inserted and brought into contact with the rear edges or backs of the knives 5 to advance them toward the periphery of the cylinder. These circumferential grooves intersect the knife-seats, as will be understood by reference to Fig. 2.

In addition to the function of securing the knives in place the holding-strips 5 perform the function of chip-breakers, in that the knives are arranged in contact with the rear walls of the knife-seats or grooves 2, and hence cause the outer edges of the wedges to 15 precede the knife edges in the operation of the cutter-head. Chips cut from the surface of the board by the knives are turned up into contact with the outer edges of the wedges, and hence are detached or broken to prevent 20 the choking or clogging of the cutting devices.

The adjustment or removal of the knives (as for the substitution of other knives or bits) may be accomplished by the simple 25 loosening of the holding-strip-adjusting devices, and hence without the removal of said strips.

In the drawings the longitudinal knife-seats are formed parallel with the axis of the 30 cylinder; but it is obvious that, as in the ordinary practice, a shearing cut may be obtained by disposing the seats diagonally with relation to the axis or extending them spirally of the surface of the cylinder; but I 35 have deemed it unnecessary to illustrate this arrangement for the reason that knives heretofore have been arranged otherwise than parallel with the axis of the cylinder.

It will be understood that in practice various changes in the form, proportion, and the 40 minor details of the construction may be resorted to without departing from the spirit or sacrificing any of the advantages of the invention.

Having described my invention, what I claim is—

1. A cutter-head having a cylinder provided with longitudinal knife-seats, a cross-sectionally-dovetailed gib fitted in the channel in the floor of one of the knife-seats, a sectional strip fitted in the knife-seat for holding a knife in its adjusted position, and bolts connecting the sections of the strip with said gibs, substantially as specified. 45

2. A cutter-head having longitudinal cross-sectionally-tapered knife-seats, cross-sectionally-wedge-shaped knife-holding strips fitted in said seats, gibs mounted in the knife-seats adjacent to the floors thereof, and strip-adjusting bolts engaged with said gibs and extending through the strips to their outer edges, substantially as specified. 55

3. A cutter-head having a cylinder provided with longitudinal cross-sectionally-tapered knife-seats, knife-holding strips fitted in said seats, cross-sectionally-dovetailed gibs fitted in cross-sectionally-dovetailed ways in the floors of the knife-seats, and bolts engaged with said gibs and extending to the outer edges of the strips to secure the latter at the 60 desired adjustment, substantially as specified. 65

4. A cutter-head having a cylinder provided with longitudinal knife-seats, and adjustable means fitted in said knife-seats to secure knives at the desired adjustment, the cylinder being provided with circumferential grooves intersecting the knife-seats to give access to the rear edges or backs of the knives, substantially as specified. 75

In testimony that I claim the foregoing as my own I have hereto affixed my signature in the presence of two witnesses.

CHRISTIAN ANDERSON.
